United States Patent Office.

JOSHUA PUSEY, OF PHILADELPHIA, PENNSYLVANIA.

Design No. 2,927, dated February 4, 1868.

DESIGN FOR A TOP.

The Schedule referred to in these Letters Patent and making part of the same.

TO ALL WHOM IT MAY CONCERN:

Be it known that I, JOSHUA PUSEY, of the city of Philadelphia, county of Philadelphia, and State of Pennsylvania, have originated a Design for "Tops," of which the following is a full, clear, and exact description, reference being had to the accompanying drawing, making a part of this specification.

My top is of a circular form, and rounded on the outer edge. Underneath, and commencing from the edge, it is made slightly concave until it nearly reaches the centre, where it now gradually rises and forms a cone, as shown in dotted lines, Figure 2. The upper part is formed in the same manner as the lower part, with the exception that it slightly rises in the centre, and then terminates abruptly and forms a shoulder, and is then again continued up straight and pointed, in the manner as shown in the drawing.

Having thus described my invention, what I claim, and desire to secure by Letters Patent of the United States, is—

The design for tops, herein set forth and shown.

JOSHUA PUSEY.
